UNITED STATES PATENT OFFICE

CHARLES H. CHALMERS, OF MINNEAPOLIS, MINNESOTA

OIL BURNER REGULATING AND RELIEF DEVICE

Application filed May 12, 1930. Serial No. 451,587.

This invention relates to pressure fluid feeding systems, such as are employed in oil burners and especially to pressure regulating and relief devices for use in such systems.

5 In high pressure oil burning systems, means such as a pump is used for feeding the fuel to the feed regulating valve under relatively high pressure, and it is essential to prevent the flow of fuel to the discharge nozzle until 10 the pressure is built up to a point where the oil will atomize and be readily ignited when discharged. It is also desirable to have the feed regulating valve positively prevent dripping of the oil the moment the burner and 15 pump are shut off.

To secure adequate pressure of such oil burner systems, and to allow for variance in the delivery of the pump or other circulating device, the system and pump are so constructed that the pump will deliver a greater amount of oil to the regulating valve than may actually be discharged by the nozzle. Various means have been provided for returning the surplus oil to the fuel tank after normal operating pressure has been built up in 20 the system. Regulating and relief valves of the diaphragm type have been extensively used for this purpose, but such diaphragm valves have been objectionable because they 25 are expensive to manufacture, delicate in structure, unsightly and clumsy and because acid, present in the fuel, often eats the diaphragm.

To my knowledge, there have been a few 30 feed regulating valves on the market of the spring pressed plunger type, but prior to my invention these have not been associated with a relief valve. The plungers in such valves are slidable in a barrel or cylinder and it is 35 usually impossible to prevent leakage of oil between the barrel and plunger to the rear end of the plunger. This leakage causes a back pressure to be built up on the spring side 40 of the plunger which often renders the valve 45 inoperative.

It is an object of my present invention to provide in fluid feeding systems of the high pressure type, such as oil burning systems, a simple, compact and comparatively inexpensive pressure regulating and relief device, 50 which will overcome the objections previously referred to, common to oil burners commercially sold at this time, which will function perfectly regardless of substantial variations in the pressure of the fuel, which will 55 positively prevent leakage and dripping, and which will cooperate nicely with standard equipment used in oil burner systems at this time.

It is a further object to provide a device of 60 the class described, wherein two valves of the spring-pressed plunger type are disposed side by side in parallel barrels, one controlling the initial feeding of fuel at a predetermined pressure to the discharge nozzle and the other 65 controlling the actual working pressure and the return of excess fuel delivered by the pump, or other circulating device, and wherein provision is made for preventing the accumulation and back pressure of oil at the 70 rear ends of the two said plunger valves by efficiently draining and returning any oil from the rear ends of the plungers to the return line communicating with the fuel tank. 75

Another object is to provide a device of 80 the class described wherein the said plunger valves are counter-bored to receive the actuating springs, thereby making it possible to greatly reduce the lengths of the barrel, lighten the plungers, and make a much more compact and ornamental device.

It is further an object to provide a device 85 of the class described, which will obviate the objectionable "chattering" or rapid reciprocating of the valve proper, which is common in most valves used for this work at the present time, and to also construct said device in the form of a unit having a rugged intake stem so constructed that connections with the 90

fuel line may be made thereto and the entire unit secured to a casting or casing of the oil burner thereby.

Another object is to provide readily accessible means for effecting the regulation of the two plunger valves, and for permitting the valves proper to be oscillated in their seats to perfectly seat the valves and to check the seating thereof.

10 These and other objects and advantages of the invention will be fully set forth in the following description made in connection with the accompanying drawings, wherein like reference characters refer to similar parts 15 throughout the several views and wherein;

Fig. 1 is a diagrammatical view showing an embodiment of my invention operatively connected in an oil burner system;

20 Fig. 2 is a vertical section taken longitudinally through my relief and feed regulating device; and

25 Fig. 3 is a cross section taken on the line 3—3 of Fig. 2, showing the port connecting the rear ends of the two valve barrels, and a 30 suitable means for effecting the oscillation or seating of the valve plungers.

In the embodiment of the invention illustrated, my relief and feed regulating device, designated as an entirety by the letter A, is 35 connected at its intake end with the feed pipe F of a high pressure oil burning system, while the relief discharge is connected by the return pipe R with the fuel tank T. The feed line F, from tank T passes through a suitable 40 strainer S, and a pump P or other device for setting up a circulation of fuel under pressure is interposed in the feed line, preferably between the strainer and the intake of the feed regulating and relief device.

45 The intake 4 of my device, preferably, comprises an elongated stem of considerable thickness and strength having the axial, vertical intake port 4^a which communicates at its upper end with a common horizontal passage or port 5 connecting with the lower ends of two vertically disposed cylindrical barrels 6 and 7, respectively. It will be noted that the barrels 6 and 7 are disposed side by side in juxtaposition with their axes par- 50 allel. I find it convenient to form both barrels of similar bore and length and as shown, they have open upper ends which may be closed in a manner hereinafter described.

Below barrel 6 is a feed discharge passage 55 comprising an axial port 8 having a valve seat 8^a, said port communicating at its lower end with a somewhat larger laterally extending port 9^a which is formed in the nozzle attachment portion or stem 9 of my device. As 60 shown, the discharge nozzle 10 with the nozzle head N at the outer end thereof is threadedly secured to the stem 9.

An axial port 11 communicates with the lower end of the relief valve barrel 7, said 65 port communicating at its lower end with a

laterally extending return port 12^a formed in a horizontal return stem 12. A tapered valve seat 11^a is disposed in the upper end of port 11. The fuel return pipe R is suitably connected with stem 12.

70 In the construction of my device, the intake stem 4 nozzle-attachment stem 9, return stem 12 and the valve barrels 6 and 7 are preferably cast or integrally formed for purposes later to be explained.

An initial pressure and feed regulating plunger 13 is slidably disposed in barrel 6, said plunger, as shown, having a diminished lower end terminating in a pointed conical valve 13^a, which accurately fits the valve seat 8^a. The upper or rear end of plunger 13 is deeply counter-bored to receive the greater portion of an actuating spring 14, for urging said valve to closed position. Suitable means may be provided to facilitate rotary oscillation of the valve 13^a in its seat which may, if desired, consist in a pair of diametric slots 13^b formed in the upper annular end of plunger 13. The upper end of coiled spring 14 reacts against an adjustable abutment plug 15 which may be inserted from the upper and open end of the barrel 6, and which has threaded engagement with the interior of said barrel to facilitate regulation thereof. Plug 15 may have a boss provided with a slot 15^a for receiving a screw driver to facilitate adjustment and removal thereof. The open upper end of barrel 6 is tightly closed by means of a suitable flanged cap 17, screw-threaded to the interior and upper end 100 of the barrel 6 and provided with a packing washer 18.

Within relief barrel 7, a plunger 19 is slidably disposed for regulating the working feed pressure and for also relieving excess fluid pumped, said plunger having a counter-bored outer or rear end in which a spring 20 is nested, similar to the nesting of spring 14 in the plunger 13. Spring 20 reacts against an abutment plug 21 at its upper end, adjustably threaded in the interior and upper end of barrel 7, and a removable cap 22 closes the open upper end of barrel 7 and is provided with a packing washer 22^a.

The lower end of plunger 19 has an externally threaded diminished stud 19^a which is surrounded by a flexible washer 23 of the pump washer type, said washer being clamped by means of a nut 23^a against the shoulder at the lower end of the body portion of plunger 19. The depending stud 19^a terminates in a truncated conical valve 19^b fitting seat 11^a, and an axial drain port 24 extends through stud 19^a extending from the lower extremity of said stud, and communicating with the counter-bored upper end of the plunger. A very small leakage groove or port 19^c may be formed in the exterior surface of valve 19^b.

115 The upper ends of the two barrels 6 and 7

are interconnected by means of a horizontal port 25 so that any fluid accumulating in barrel 6 due to leakage between the plunger 13 and said barrel may pass to the rear or outer 5 end of plunger 19 which is provided with the axial drain port 24.

Apertures 26 and 27 may be formed through the cap 17 and the portion of the casting or member A which is disposed between barrels 6 and 7 for the purpose of 10 accommodating a sealing wire to prevent tampering or adjustment of the initial feed valve after it has been set.

15 *Operation*

In operation, the tension of the actuating springs 14 and 20 are so adjusted by properly positioning their plugs 15 and 21, that the initial feed valve 13 will be held closed until 20 the pressure upon the lower end thereof exceeds a desired point, for example, sixty pounds per square inch. The actuating spring 20 of the controlling and relief plunger 19 is so adjusted that said plunger will 25 remain closed until the pressure against the lower end exceeds the desired working point, say for example, ninety pounds per square inch. When the pump is operated, pressure will be built up in the system and applied 30 against the lower ends of plungers 13 and 19, and when this pressure is adequate to thoroughly atomize the discharged fluid, valve 13a will be raised and the fluid will be sprayed from the nozzle. Upon further operation, 35 pressure will be increased to the point where the working pressure control plunger 19 will be raised permitting the surplus oil to be returned through port 11, port 12a and return pipe R to the fuel tank. After the initial 40 feed controlling valve 13 is adjusted for a predetermined point, a sealing wire or band is preferably inserted through the apertures 26 and 27, as it is not usually desirable for the user to adjust this valve.

45 In the operation of a sliding plunger pressure regulating device, small amounts of oil are bound to leak between the plungers and the barrels. In my device, the accumulating leakage in barrel 6 will pass through the interconnecting port 25 into the upper end of barrel 7 and will be drained through the axial passage 24 in plunger 19 and returned to the return pipe R. It will be seen, therefore, that it is impossible for pressure to be built up 50 at the rear or outer ends of either of the plungers to effect the efficiency or operation of my device. The interconnection of the upper ends of the barrels in cooperation with the axial drain port in the plunger 19 provides a simple means for draining the leakage without requiring any drilling or tapping of the casting A and both barrels will be 55 efficiently drained.

No leakage of oil can occur at the upper 60 ends of barrels 6 and 7, due to the fact that

the caps 17 and 22 with their associated packing washers form a fluid tight joint at said ends.

It will be noticed that my entire pressure regulating and relief device is perfectly balanced upon the intake stem 4 and is entirely mounted within the integral casting A. The elongated intake stem 4 is ruggedly constructed and may be passed through an opening in casing or casting C, as shown in Fig. 1, 70 and secured to a boss B therein by suitable means, such as a set screw. The said depending stem 4, thus will support the entire device as well as the connected ends of the feed and return pipes and also the nozzle pipe 10. 80

The tension of springs 14 and 20, and consequently, the actuating pressure upon plungers 13 and 19, respectively, may be readily varied by removing caps 17 and 22, inserting a screw driver, or other tool, and turning 85 the plugs 15 and 21, respectively. It will also be seen that the plugs 15 and 21, and the springs 14 and 20, may be removed from the open upper end of the barrels 6 and 7, whereafter, a tool having an end, similar to 90 a large screw driver, may be inserted in the slotted portions of the upper ends of plungers 13 and 19 for oscillating the plungers to properly seat or inspect the seating of the valves 8a and 19b, respectively. 95

The deep counter-boring of the upper portions of the plungers and nesting of the springs therein greatly economize upon the length of the barrels required for the two valves and result in a compact, ornamental 100 and relatively light unitary structure. The small leakage groove 25 in the surface of relief valve 19b permits a small amount of oil to be returned before the pressure is adequate to open relief valve 19b.

From the foregoing description it will be seen that I have provided a simple, compact and highly efficient pressure regulating and relief device, especially adapted for pressure oil burning systems and capable of wide general usage in pressure fluid feeding systems of many types. 110

It will, of course, be understood that various changes may be made in the form, details, arrangement and proportions of the parts without departing from the scope of my invention, which, generally stated, consists in a device capable of carrying out the objects above set forth, in the novel parts and combinations of parts disclosed and defined in the appended claims. 115 120

What is claimed is :

1. A pressure regulating and relief device, comprising a barrel having a yieldingly actuated plunger valve slidably disposed therein, a fluid intake communicating with the inner end of said barrel to subject said plunger to the pressure of incoming fluid, a discharge passage having a valve seat therein with

which said plunger valve cooperates, and an axial drain passage through said plunger valve communicating with said discharge passage.

5 2. A pressure regulating and relief device for fluid feeding systems having in combination, a pair of barrels, a pair of plunger valves slidably mounted in said barrels and yieldingly urged inwardly, an intake passage 10 communicating with the inner ends of both of said barrels to subject said plungers to the pressure of incoming fluid, a feed discharge having a valve seat therein with which one of said valves cooperates, a relief 15 discharge having a valve seat therein with which said other valve cooperates, and connections between the outer ends of said barrels and the relief discharge adapted to drain off fluid which leaks into the outer portions 20 of said barrels between said barrels and said plungers to prevent accumulation of back pressure against said plungers.

3. A pressure regulating and relief device for fluid feeding systems having in combination, a pair of plunger containing barrels 25 disposed side by side, plunger valves slidably mounted in said barrels, a fluid intake communicating with the inner ends of said barrels to subject said plungers to the pressure 30 of incoming fluid, a feed discharge passage having a valve seat therein, with which one of said valves cooperates, and a relief discharge passage with which said other valve cooperates to control the working pressure, the outer 35 ends of said barrels being interconnected, and a drain passage communicating with the outer portion of one of said barrels behind its plunger to drain off fluid leaking between 40 said plunger and said barrel.

4. A pressure regulating and relief device 45 for fluid feeding systems having in combination, a pair of plunger containing barrels disposed side by side, plunger valves slidably mounted in said barrels, a fluid intake communicating with the inner ends of said barrels to subject said plungers to the pressure of incoming fluid, a feed discharge passage having a valve seat therein, with which one of said valves cooperates, and a relief discharge 55 passage with which said other valve cooperates to control the working pressure, the outer ends of said barrels being interconnected, said second valve having an axial drain port therethrough communicating with the said relief discharge passage.

5. A pressure regulating and relief device 60 for fluid feeding systems comprising a member having an intake passage therein connected with a fluid supply conduit, a feed discharge passage and a relief discharge passage connected with a fluid return conduit, a pressure controlling and relief valve within said member, said member having an elongated stem providing one of said passages and also adapted to be inserted through an

apertured member to support the entire device and said connections with the supply and return conduits.

6. A pressure regulating and relief device 70 for fluid feeding systems comprising a member having an intake passage therein connected with a fluid supply conduit, a relief discharge passage connected with a fluid return conduit, a plunger valve slidably mounted in said member for controlling the flow of fluid through said relief discharge, said plunger having a longitudinally disposed drain port therethrough communicating with said relief discharge passage to drain fluid 75 seeping between the peripheral wall of said plunger and said first mentioned member.

7. A pressure regulating and relief device 80 for fluid feeding systems comprising a plunger-containing barrel having a fluid intake 85 communicating with one end thereof, and also having a relief discharge passage communicating with the same end, a valve seat in said relief discharge passage disposed axially of said barrel a plunger slidably mounted in 90 said barrel and urged in the direction of said seat, said plunger carrying a reduced valve element adapted to cooperate with said seat and having an axial drain port communicating with said relief discharge passage for 95 draining fluid seeping between the peripheral wall of said plunger and said barrel.

8. A pressure regulating and relief device 100 for fluid systems comprising a plunger-containing barrel having a fluid intake communicating with one end thereof and also having a relief discharge passage communicating with the same end and disposed substantially axially of said barrel, a valve seat in said relief discharge passage, a plunger slidably 105 disposed in said barrel, an abutment in the outer portion of said barrel threadedly engaging said barrel for longitudinal adjustment, a coiled spring interposed between said abutment and the outer end of said plunger and a fluid-tight closure for the outer end of said barrel for rendering said abutment and plunger accessible for adjustment and replacement and for positively preventing 110 leakage of fluids from said barrel.

9. A pressure regulating and relief device 115 for fluid feeding systems comprising an integral member having formed therein a pair of plunger-containing barrels disposed side by side, the inner ends of said barrels being interconnected, an elongated stem disposed centrally and longitudinally of said member and integrally formed therewith for the dual purpose of providing a fluid passage to the inner ends of said barrels and for also constituting a mechanical support for the device and its connections.

10. A duplex fluid pressure regulating valve comprising, in combination, a body portion having two adjacent open-ended cylinders therein terminating at the front end 120

in a common fluid chamber, said fluid chamber having an inlet and two outlets for the fluid, pistons slideable in said cylinders, springs pressing against the rear of said pistons, closure members for the rear ends of said cylinders, means for closing said outlets operated by said pistons, a drainage duct connecting the spring chambers of both cylinders and connecting with the fluid duct beyond the second outlet closing means, the first piston being adapted to operate at a lower fluid pressure in said common chamber than the second piston.

In testimony whereof I affix my signature.

CHARLES H. CHALMERS.
